UNITED STATES PATENT OFFICE

HARRY DIXSON, OF PELLA, IOWA, ASSIGNOR TO ROLSCREEN COMPANY, OF PELLA, IOWA

ROLL-SCREEN INSTALLATION FOR CASEMENT WINDOWS

Application filed November 7, 1929. Serial No. 405,374.

The object of my invention is to provide a rollscreen installation for steel casement windows of simple, durable and comparatively inexpensive construction.

5 More particularly, it is my object to provide an installation wherein a rollscreen may be installed upon a steel casement window employing parts of such standard steel casement as a means for mounting the entire rollscreen thereon without the use of any additional fastening elements or the like.

A further object is to provide an installation wherein the rollscreen casing may be mounted upon supporting elements, which 15 supporting elements are frictionally supported upon parts of the steel casement, and where such supports provide guide means for the side edges of the screen and at the same time serve as a weatherstrip feature between 20 a portion of the casement frame and the window sash thereof.

A further object is to provide a head spacer element and a sill spacer element adapted to be frictionally mounted upon the head and 25 sill portions of the casement frame and to serve as filler elements between the two supporting elements forming a part of the rollscreen installation.

It may be here mentioned that standard 30 steel casements are provided with a marginal flange around the window opening, and that the hinged sash member is normally arranged to abut against the marginal flange. The point where the hinged sash member abuts 35 against the flange is normally referred to as the "meeting bite" of the sash with its casement. In my installation, I provide a plurality of members which frictionally receive the marginal flange, whereby the parts of my 40 rollscreen installation are securely held in position relative to the casement window, and it is upon these parts that I mount a rollscreen casing and other parts necessary to provide a complete rollscreen installation and structure for a steel casement window.

A further and more specific object is to provide supporting elements having oppositely opening channel portions or grooves, one to receive the side or jamb flanges of the casement and the other to receive a screen guide 50

or the side edges of the screen itself, the two channel portions being arranged in spaced parallel planes.

A further object is to provide a rollscreen casing adapted to be supported by a pair of supporting elements, having portions bendable upon the casing itself for retaining the casing in position, the casing itself serving as a spacer for normally holding the supporting elements in spaced position and in installed position upon the casement frame. 55

It is also an object of my invention to provide a rollscreen installation wherein the parts can be assembled without the use of any special tools or the like and without the use 60 of fastening means, employing certain parts of the present standard steel casements as a means for mounting the rollscreen thereon, the installation being neat and pleasing in appearance and in no way interfering with 65 the plaster jambs or the beauty afforded by steel casements themselves, the screen being mounted within the home or building, thus making neatness in appearance an essential objective. 70

With these and other objects in view, my invention consists in the construction, arrangement and combination of the various parts of my rollscreen installation for casement windows, whereby the objects contemplated are attained, as hereinafter more fully set forth, pointed out in my claims, and illustrated in the accompanying drawings, in which: 75

Figure 1 is a plan view of the interior of 80 a building wall with a steel casement therein in partly open position, together with my rollscreen installation in complete form.

Figure 2 is a vertical, sectional view taken on the line 2—2 of Figure 1, with the window 85 sash in closed position.

Figure 3 is a perspective view of one of the supporting elements and its association with a screen casing, the screen and guide therefor.

Figure 4 is a similar perspective view with 90 the parts in assembled position.

Figure 5 is a horizontal, sectional view taken on the line 5—5 of Figure 1.

Figure 6 is a vertical, sectional view taken on the line 6—6 of Figure 4. 100

Figure 7 is a detail, sectional view taken on the line 7—7 of Figure 5.

Figure 8 is a sectional view taken on the line 8—8 of Figure 4.

Figures 9 and 10 illustrate in diagrammatic form the process or method used in installing the rollscreen installation on a casement window where the plaster header of the wall is of the kind shown in Figure 2.

10 In the accompanying drawings, I have used the reference character A to indicate generally a building wall, which may be of either wood or brick construction and coated on the inside with ordinary plaster 10.

15 The building wall A includes a window opening B, in which is mounted a steel casement and sash C. The steel casement is of the standard kind and includes a casement frame 12, having an inwardly extending marginal flange 14. The flange 14 may be referred to as a marginal or inwardly directed flange around the window opening defined by the casement itself.

An out-turned marginal flange 16 is also 25 formed as part of the casement frame and rests against the building wall on the outside thereof, as clearly illustrated in section in Figure 2 of the drawings.

Within the casement frame is mounted a 30 window sash 18 adapted for hinged movement relative to the casement frame.

On the inside of the flange 14 is mounted a stop or plate 20 adapted to coact with the cam locking element 22 carried by the window sash 18. A handle 24 is employed for operating the cam member 22.

It may be further mentioned that the stop or plate 20 has an inclined face, so that operation of the handle 24 will cause the parts to 40 engage for retaining the window sash 18 in closed position.

The parts just described are of ordinary construction as now found in practically all of the so-called standard steel casements.

45 For purposes of further explanation of my rollscreen installation, I use the reference numeral 26 to indicate the two sides or jamb portions of the peripheral flange 14. 28 indicates the flange at the head of the frame, 50 and 30 the flange at the sill of the frame.

My rollscreen installation is adapted to coact with the inwardly directed flange 14.

My installation includes a pair of supporting elements D. Each supporting element is formed to provide a pair of oppositely opening channel portions 31 and 32. The channel portions 31 and 32 are spaced apart and connected together by a web or the like 34. In the actual construction of the supporting elements D, I employ one piece of metal, which is so formed as to provide a complete channel portion 31 and one wall of the channel portion 32. The other wall of the channel portion 32 is formed by another piece of metal 60 arranged in spaced relation to one wall of the

channel 32 and in contacting relationship to the web or connecting portion 34. The two walls which form the web 34 are spot-welded together, all as clearly illustrated in Figure 3 of the drawings.

It will be noted that the channel portions are arranged so that they open in opposite direction, are parallel to each other, and spaced apart.

70 Each supporting element includes an upwardly extending lip 36 formed upon the inner wall of the channel groove or portion 32.

The channel portions 31 are arranged to receive the jamb flanges 26 of the casement frame. The channel portions frictionally receive such flanges 26.

80 The outside wall of each channel portion 31 is positioned between the meeting bite of the window sash and the casement frame, thus serving as a weather strip feature between the casement frame and the sash thereof.

85 It will be understood that the parts just described, which form the supporting elements are of sheet metal, and thus inherently resilient, so that they not only frictionally engage the side jambs 26, but also serve as a weather strip feature.

90 A rollscreen casing 38 is used, and such casing is disclosed in my Letters Patent No. 1,730,649, issued October 8, 1929.

95 One corner of the casing as at 40 includes a notch or cut-out portion. This portion is in reality a continuation of the discharge opening 42, through which the screen may be withdrawn from the casing, as will be hereinafter more fully set forth.

100 It will be noted that the bearing members 44 of the casing are spaced inwardly a slight distance from the ends of the casing. The outer wall of the casing 38 as at 46 is arranged to slip into the upper end of the groove or channel portion 32. The casing 38 is thus retained in position relative to the two supporting elements D. The lip 36 is thereafter bent over and brought into engagement with the upper side of the casing 38.

105 The assembled position of the casing and its supporting member for each end is clearly illustrated in Figure 4 of the drawings.

110 Within the casing 38, I provide a rollscreen assembly E, which includes a spring-actuated roller 48 and a screen 50. The lower free end of the screen has a stiff binder 52 mounted thereon which has an inwardly directed finger ledge 54.

115 The screen 50 is permitted to pass out of the casing 38 through the discharge opening 42. Within the channel portion 32 of each supporting element D, I mount a screen guide or track 56. The track 56 includes a flat fastening flange adapted to telescopically fit into the groove or channel 32 and to be frictionally retained therein. The guide or track 120

125

130

portion proper is of tubular outline and is provided with a slit opening arranged lengthwise thereof, and it is through this slit opening that the side edges of the screen 50 are received.

The retaining elements 58 may be employed upon the side edges of the screen, and are normally received within the guides or tracks 56. The guides or tracks 56 are positioned below the screen casing 38. Friction shoes or blocks 60 are fastened to the ends of the binder 54 and travel within the guide tracks 56. Locking elements 62 are carried by the tracks and coat with the finger ledge 54 when the screen is in withdrawn position for retaining it in such position against the action of the spring roller assembly 48.

It will be noted that the rollscreen assembly including the casing, tracks and the like, are all mounted and supported upon the supporting elements D. The supporting elements D are in turn frictionally retained on the side or jamb flanges of the casement proper.

25 A head spacer element 64 is secured to the head flange 28 of the casement and spans or fills the distance between the casement and the rollscreen as well as between the two supporting elements D.

30 The head spacer element is formed with an upwardly opening channel portion 66, which receives the downwardly extending head flange 28.

A down-turned marginal flange 68 is formed on the inner edge of the spacer element 64 and this is in contact with the outer wall of the casing 38.

35 A sill spacer element 70 is also provided and it in turn has a downwardly opening channel groove 72 to normally receive the upwardly extending sill flange 30. The spacer element 70 is positioned between the two supporting elements D and prevents their movement toward each other, and is formed with a portion 74 normally arranged to be positioned just below the lower edge of the guide tracks 56.

40 It will be noted that the sill spacer 70 is positioned a short distance up above the lower ends of the supporting elements D.

The spacer elements 64 and 70 prevent removal of the supporting elements D and likewise provide a fly-tight joint, due to the fact that it is necessary to have the screen casing and guide tracks therefor spaced inwardly a slight distance from the inner face of the casement frame.

Practical installation

45 The practical installation of my rollscreen installation may be briefly described as follows:

The steel casement window is placed in position in the ordinary manner and forms a standard portion or part of the building

structure. The problem of screening the window then presents itself.

It is impossible to have a screen mounted on the outside of a casement window, due to the peculiar nature of the casement itself, in that the window sash opens outwardly and is of the hinge mounted type.

50 My screen is mounted on the inside of the casement and I take one of the pair of supporting elements and fit it into the notch 40 of the casing, and then place it over one of the side jamb flanges of the casement. The other supporting element is then fit into the other side of the casing. The lip 36 is bent over. The casing is arranged at an angle while the installation is taking place. (See Figure 9 for illustration of same.)

55 A rubber hammer may be used for tapping the members in position or they may be simply pushed under slight pressure to position. The supporting elements are thus frictionally retained upon the casement without other fastening means.

60 The head spacer member or element 64 is then forced onto the head flange 28 of the casement with its ends positioned between the two supporting elements D, and particularly between the two channel portions of each supporting element. (See Figure 10.) The sill spacer element 70 is forced under pressure onto the sill flange 30 and likewise arranged so that its ends are positioned between the two supporting elements D.

65 After the casing is in position and the two supporting elements in engagement with the flange of the casement, the entire structure is in complete relationship relative to a steel casement and completely mounted thereon, without the use of any peculiar fastening means or elements.

70 The rollscreen installation can be easily and quickly removed if it is desired for any cause.

75 My present rollscreen installation has been in actual use and has proven successful in such use.

80 I may here mention that after the complete installation is had, then the entire peripheral flange 14 of the casement window is covered by the channel portions of the spacer elements and supporting elements, and a weatherstrip feature is provided, extending around the casement frame adjacent the point where the window sash engages therewith.

85 It is necessary to incline the casing and one supporting element as illustrated in Figure 9, due to the fact that the plaster header above the casement is quite close to the upper rail of the casement. If plenty of space is had, then the rollscreen can be installed by placing both supporting elements on the side jamb flanges and thereafter mounting the box thereon. While I have shown the supporting elements as fabricated from several pieces, it will of course be understood that

it might be formed in a rolling machine of one piece of metal.

Some changes may be made in the construction, and arrangement of the various parts of my rollscreen installation for casement windows without departing from the real spirit and purpose of my invention, and it is my intention to cover by my claims, any modified forms of structure or use of mechanical equivalents, which may be reasonably included within their scope.

I claim as my invention:

1. For use with a window frame having a flange at each side thereof, a rollscreen installation including supporting elements having channel portions to receive said flanges whereby said supporting elements are supported relative to the window frame, a casing carried by the upper ends of said supporting elements, and said supporting elements having channel means longitudinally thereof in alignment with the side edges of a rollscreen.

2. For use with a window frame having a flange at each side thereof, and a flange at the bottom and at the top thereof, a rollscreen construction including supporting elements having channel portions to receive said flanges whereby said supporting elements are supported relative to the window frame, a rollscreen casing carried on the upper ends of said supporting elements, and spacer elements having channel portions to receive the flanges at the bottom and top of said window frame whereby said spacer elements are supported relative to the window frame, said spacer elements being interposed between said supporting elements to prevent their removal from their supported positions, guide means carried by said supporting elements to receive the side edges of a rollscreen.

3. For use with a steel casement window having an inwardly directed flange, and a movable window engageable with said flange a rollscreen construction including a pair of supporting elements, a bottom spacer element and a top spacer element all frictionally supported on said flange, a rollscreen casing carried by said supporting elements, and a channel guide means carried by said supporting elements to receive the side edges of a rollscreen when in extended position.

4. For use with a steel casement window having an inwardly directed flange, a rollscreen construction including a pair of supporting elements, a bottom spacer element and a top spacer element all frictionally supported on said flange, a rollscreen casing carried by said supporting elements, and means for receiving the side edges of a rollscreen when in extended position, said means being carried by said supporting elements.

5. In combination with a steel casement window having an inwardly directed flange, a rollscreen construction including a pair of supporting elements, a bottom spacer element

and a top spacer element all supported on said flange a rollscreen casing carried by said supporting elements, and means for receiving the side edges of a rollscreen when in extended position, said supporting elements having channel grooves to receive said means.

6. In combination with a steel casement window having an inwardly directed flange, a rollscreen construction including a pair of supporting elements, a bottom spacer element and a top spacer element all frictionally supported on said flange, said bottom and top spacer elements preventing removal of said supporting elements, a casing carried by said supporting elements, and means for receiving the side edges of a rollscreen when in extended position, said supporting elements having channel grooves to frictionally receive said means.

7. For use with a window frame having a flange at each side thereof, a rollscreen installation including, supporting elements having channel portions to receive said flanges whereby said supporting elements are supported relative to the window frame, said elements having channel grooves formed therein opening oppositely from said channel portions, screen guides received in said channel grooves, a rollscreen casing supported by the supporting elements and said screen guides being adapted to receive the side edges of a screen when extended.

8. For use with a window frame having a flange at each side thereof, a rollscreen construction including supporting elements having channel portions to receive said flanges whereby said supporting elements are supported relative to the window frame said elements having channel grooves formed therein screen guides received in said channel grooves, a rollscreen casing, said casing having one wall received in said channel grooves whereby the casing is supported by the supporting elements and is aligned with said screen guides.

9. For use with a window frame having a flange at each side thereof, a rollscreen construction including supporting elements having channel portions to receive said flanges whereby said supporting elements are frictionally supported relative to the window frame said elements having channel grooves formed therein screen guides received in said channel grooves, a rollscreen casing, said casing having one wall received in said channel grooves whereby the casing is supported by the supporting elements and is aligned with said screen guides and a lip on each of said supporting elements bendable over said rollscreen casing to prevent dislodgement of the rollscreen casing from the supporting elements.

10. For use with a window frame having side, bottom and top flanges projecting inwardly with respect to the window opening

defined by the frame, a screen installation including supporting elements having outwardly opening channel portions to receive said side flanges, said supporting elements having inwardly opening channel grooves, a casing carried by the upper ends of said supporting elements and a screen in said casing adapted to be extended therefrom with its side edges in alignment with said channel grooves.

11. For use with a steel casement window frame having side, bottom and top flanges projecting inwardly with respect to the window opening defined by the frame, rollscreen installation including supporting elements having outwardly opening channel portions to receive said side flanges, and inwardly opening channel grooves to receive screen guides, a rollscreen casing having one wall received in the upper ends of said channel grooves whereby the casing is supported by said supporting elements, a head spacer element having an upwardly opening channel portion to receive the top flange of said window frame and a sill spaced element having a downwardly opening channel portion to receive the bottom flange of said window frame, said head and sill spacer elements being interposed between said supporting elements, between the rollscreen casing and said top flange and spanning the space between a screen when in its lowermost position and said bottom flange.

12. For use with a steel casement window frame having side, bottom and top flanges projecting inwardly with respect to the window opening defined by the frame, a screen installation including supporting elements having outwardly opening channel portions to receive said side flanges, said supporting elements having inwardly opening channel grooves, a casing having one wall received in the upper ends of said channel grooves whereby the casing is supported by said supporting elements, and in alignment with said channel grooves, a head spacer element having an upwardly opening channel portion to receive the top flange of said window frame and a sill spacer element having a downwardly opening channel portion to receive the bottom flange of said window frame, said head and sill spacer elements being interposed between said supporting elements, between the screen casing and said top flange and spanning the space between a screen when in its lowermost position and said bottom flange.

13. In combination with a steel casement window frame having a flange and window sash movable relative thereto and engageable with the flange, a rollscreen installation for said casement including supporting elements each having oppositely opening and spaced channel portions, one of said channel portions receiving said flange, the other in

alignment with the screen of the rollscreen, a screen casing carried by said elements for preventing their movement towards each other, a sill spacer element also supported on said flange for holding the lower ends of said supporting elements from movement towards each other and a filler element carried by said flange and filling the space defined by the supporting elements, the casement frame and the screen casing.

14. In combination with a steel casement window frame having a flange and window sash movable relative thereto and engageable with the flange, a rollscreen installation for said casement including supporting elements each having oppositely opening and spaced channel portions, one of said channel portions receiving said flange, the other in alignment with the screen of the rollscreen, a screen casing carried by said elements for preventing their movement towards each other, a sill spacer element also supported on said flange for holding the lower ends of said supporting elements from movement towards each other.

15. In combination with a steel casement window having a flange around the opening defining the window, a rollscreen installation including a pair of supporting elements each having a pair of oppositely opening channel portions arranged in different parallel planes, a bottom spacer element, a top spacer element all carried by said flange, one of said channel portions receiving the flange and the other in alignment with the rollscreen, said bottom and top spacer elements preventing removal of said supporting elements from the flange.

16. In combination with a steel casement window having a flange around the opening defining the window, a rollscreen installation including a pair of supporting elements each having a pair of oppositely opening channel portions arranged in different parallel planes, a bottom spacer element, a top spacer element all carried by said flange, one of said channel portions receiving the flange and the other in alignment with the rollscreen, said bottom and top spacer elements serving as fillers to span the distance between the rollscreen and the casement window caused by arranging the channel portions of said supporting elements in different planes.

17. In combination with a steel casement window having a flange around the opening defining the window, a rollscreen installation including a pair of supporting elements each having a pair of oppositely opening channel portions arranged in different parallel planes, a bottom spacer element, a top spacer element all frictionally carried by said flange without the aid of other fastening means, one of said channel portions receiving the flange and the other in alignment with the rollscreen, said bottom and top spacer

elements preventing removal of said supporting elements from the flange.

18. In combination with a steel casement window having a flange around the opening defining the window, a rollscreen installation including a pair of supporting elements each having a pair of oppositely opening channel portions arranged in different parallel planes, a bottom spacer element, a top spacer element all frictionally carried by said flange without the aid of other fastening means, one of said channel portions receiving the flange and the other in alignment with the rollscreen.
19. In combination with a steel casement having a flange around the opening thereof, a screen installation including a pair of elements, each having a pair of channel portions formed therein, one channel opening in one direction to frictionally receive a portion of said flange of the casement whereby to support said elements in position on said casement, and the other channel opening in the opposite direction whereby it is aligned with a screen for screening the casement window opening.
20. In combination with a steel casement window having a flange around the opening defining the window, a screen installation including a pair of supporting elements, each having a pair of oppositely opening channel portions arranged in different parallel planes, a bottom spacer element and a top spacer element all carried by said flange, one of said channel portions of the supporting elements receiving the flange and the other opening towards the screen, said bottom and top spacer elements preventing removal of said supporting elements from the flange.
21. In combination with a steel casement window having a flange around the opening defining the window, a screen installation including a pair of supporting elements each having a pair of oppositely opening channel portions arranged in different parallel planes and carried by said flange, one of said channel portions receiving the flange and the other opening towards the screen, and bottom and top spacer elements serving as fillers to span the distance between the screen and the casement window caused by arranging the channel portions of said supporting elements in different planes.
22. In combination with a steel casement window having a flange around the opening defining the window, a screen installation including a pair of supporting elements each having a pair of oppositely opening channel portions arranged in different parallel planes, and frictionally carried by said flange without the aid of other fastening means by having one of said channel portions receive the flange and the other channel portion to support the screen relative to the casement window.

23. Screen mounting means for a screen applicable to a steel casement window comprising a pair of members each having oppositely opening channel portions, one of said channels adapted to frictionally receive a part of the casement and the other channel to support the screen to thereby mount the screen relative to a casement window.

24. Screen mounting means for a screen applicable to a steel casement window comprising a pair of members each having oppositely opening channel portions, one of said channels adapted to frictionally receive a part of the casement for thereby supporting it on the casement without the aid of additional fastening means and the other channel to support the screen whereby it is associated with the casement for screening the opening thereof.

25. Screen mounting means applicable for steel casement windows comprising a pair of similar opposed members, each having a channel portion to frictionally receive a part of the casement and portions projecting inwardly from the casement to support a screen and thereby maintain it relative to the casement.

26. Screen mounting means applicable for steel casement windows comprising a pair of opposed members, each having a portion to be received by a part of the casement and portions projecting inwardly from the casement to support a screen and thereby maintain it relative to the casement and a second pair of spaced members arranged between and at right angles to said first pair of members mounted on the casement to retain said first pair of members in position.

27. A method of installing a rollscreen upon a steel casement window having inwardly directed jamb flanges, comprising the placing of a channel-shaped supporting element in position to engage one jamb flange, securing a screen casing upon the upper end of the supporting element, securing a second supporting element to the screen casing, arranging the casing at an angle relative to horizontal and said last supporting element at an angle relative to vertical, moving the free end of said second supporting element towards the jamb flange to assume a vertical position and thereby raising the lower end of the screen casing upwardly, whereby it assumes a horizontal position, and securing the two supporting elements in frictional engagement with the jamb flanges.

Des Moines, Iowa, November 2, 1929.
HARRY DIXSON.
